UNITED STATES PATENT OFFICE.

BLUFORD W. BROCKETT, OF CLEVELAND, OHIO.

RESILIENT HEEL.

1,286,169.

Specification of Letters Patent.

Patented Nov. 26, 1918.

Application filed May 27, 1918. Serial No. 236,773.

To all whom it may concern:

Be it known that I, BLUFORD W. BROCKETT, citizen of the United States, residing at Cleveland, in the county of Cuyahoga and 5 State of Ohio, have invented certain new and useful Improvements in Resilient Heels, of which the following is a specification.

This invention relates to resilient heels, such as are used upon shoes and other foot- 10 wear.

The object of the invention is to provide an improved resilient heel which clings to the pavement or other surface being walked upon and therefore protects the wearer from 15 injuries which otherwise might be caused by slipping or skidding of the heel. More particularly the invention has for its object to provide a heel of this kind having transversely extending teeth or ridges which are 20 so arranged as to resist slipping movement of the heel both forwardly and toward either side, which are self-cleaning, or, in other words, which automatically free themselves from material scraped from the pavement, 25 and which heel is also more strongly reinforced against wear at its rear portion than prior heels of the same general type.

Further objects of the invention are in 30 part obvious and in part will appear more in detail hereinafter.

In the drawings, which represent one suitable embodiment of the invention, Figure 1 is a bottom plan view; Fig. 2 is a side elevation; and Fig. 3 is a perspective view 35 from beneath.

For purposes of illustration the drawings show the invention applied to a heel adapted to be secured to or embodied in the heel of a shoe. It comprises a body portion 1 which 40 may be made of rubber, a rubber composition, or any other suitable resilient material, and which is provided with a series of openings 2 through which may be driven nails or screws for securing it to the shoe. 45 The lower surface of said heel is suitably formed to provide a series of transversely extending saw-teeth 3 which in number will vary with the size of the heel and with the particular effect to be obtained. The draw- 50 ings show four teeth or projections, of which the first or the one at the front of the heel has its front surface 4 formed by the vertical surface at the front of the heel, while the last saw-tooth has its bottom surface 55 5 in a horizontal plane substantially co-incident with the sharp edges 6 of the remain-

ing teeth. The first three teeth toward the front have their back surfaces 7 sloping on a long gradual incline downwardly toward the front of the heel, where said surfaces 60 intersect along the edges 6 the front surfaces 8 of said teeth, which may be vertical but are shown as slightly inclined downwardly from the rear toward the front, so that the angle between the surfaces 7 and 8 is slightly 65 less than a right angle. This makes the edges 6 relatively sharp so that they exert a squeegee effect on the pavement and cut through and wipe off water, mud or any other foreign material lying upon the pave- 70 ment, and therefore cling or stick to the pavement.

Viewing the heel from beneath, as in Fig. 1, it will be observed that the teeth or projections 3 are also inclined laterally across 75 the heel, preferably being inclined backwardly toward each side from the central longitudinal line. Each tooth or projection therefore has two portions inclined laterally and meeting along the center line of 80 the heel in a sharp point or projection 9. When the heel is planted upon the pavement the inherent resiliency of the material causes these points or projections to bend downwardly into close or intimate contact with 85 the surface walked upon. Moreover, each half of each tooth has a sort of plow action, as any material which it may scrape up from the pavement slides along the channel in front of the tooth and is discharged 90 at the side of the heel. In other words, the teeth are self-cleaning and not likely to become clogged with material such as would otherwise interfere with their squeegee action. Finally, the lateral inclination of said 95 teeth increases the area of the horizontal surface 5 at the rear of the heel over what it would be if the teeth extended straight across the heel, and thereby forms a wide flat pad of solid material at the rear of the 100 heel which materially increases its wear resisting ability. This pad always receives the first impact of planting the heel upon the pavement, so that reinforcement at this point is of material advantage.

What I claim is:

1. A heel, comprising a body portion of yielding material having its lower portion provided with a series of ridges extending transversely of the heel and each diagonally disposed to the longitudinal axis of the heel, said ridges having a relatively long 110

face sloping forwardly and downwardly and intersecting along a sharp edge a relatively short face lying in a substantially vertical plane, thereby forming a series of saw-teeth having sharp edges which contact the pavement and exert a squeegee effect to prevent slipping of the heel thereon.

2. A heel, comprising a body portion of yielding material having its lower portion provided with a series of ridges extending laterally and rearwardly toward the sides of the heel from a longitudinal line, said ridges having a relatively long face sloping forwardly and downwardly and intersecting along a sharp edge a relatively short face lying in a substantially vertical plane, thereby forming a series of saw-teeth having sharp edges which contact the pavement and

exert a squeegee effect to prevent slipping of the heel thereon.

3. A heel, comprising a body portion of yielding material having its lower portion provided with a series of ridges inclined rearwardly from a longitudinal line toward both sides of the heel, thereby forming a series of angular forwardly extending plow points, said ridges having a relatively long face sloping forwardly and downwardly and intersecting along a sharp edge a relatively short face lying in a substantially vertical plane, thereby forming a series of saw-teeth having sharp edges which contact the pavement and exert a squeegee effect to prevent slipping of the heel thereon.

In testimony whereof I affix my signature. 35
BLUFORD W. BROCKETT.
